UNITED STATES PATENT OFFICE.

JAMES A. BROWNE, OF EAST ORANGE, NEW JERSEY.

DESIGN FOR A WATCH-CHARM OR SIMILAR ARTICLE.

SPECIFICATION forming part of Design No. 36,462, dated July 28, 1903.

Application filed June 20, 1903. Serial No. 162,455. Term of patent 7 years.

To all whom it may concern:

Be it known that I, JAMES A. BROWNE, a citizen of the United States, residing at East Orange, in the county of Essex and State of

5 New Jersey, have invented a new, original, and ornamental Design for a Watch-Charms or Similar Article; and I do hereby declare the following to be a full, clear, and exact description of the invention, such as will enable others skilled in the art to which it appertains to make and use the same, reference being had to the accompanying drawing, and to letters of reference marked thereon, which form a part of this specification.

15 The single figure of the drawing is a front

elevation of the article of jewelry especially adapted for sleeve-buttons, pendants, charms, &c., as is deemed sufficient to fully illustrate the same.

What I claim as new is—

20 The ornamental design for a watch-charm or similar article as shown.

In testimony that I claim the foregoing I have hereunto set my hand this 8th day of June, 1903.

JAMES A. BROWNE.
